UNITED STATES PATENT OFFICE.

FERNAND JAVAL, OF PARIS, FRANCE, ASSIGNOR TO HOUBIGANT, INC., OF NEW YORK, N. Y., A CORPORATION OF NEW YORK.

DESIGN FOR A BOTTLE.

Application filed April 15, 1925. Serial No. 13,133. Term of patent 14 years.

To all whom it may concern:

Be it known that I, FERNAND JAVAL, a citizen of the Republic of France, residing at Paris, France (whose post-office address is c/o Parfumerie Houbigant, 19 Rue du Faubourg Saint-Honore, Paris, France), have invented a new, original, and ornamental Design for a Bottle, of which the following is a specification, reference being had to the accompanying drawing, forming a part thereof.

In the drawing,

I claim:—

The ornamental design for a bottle substantially as shown.

FERNAND JAVAL.
